UNITED STATES PATENT OFFICE.

LOUIS MEYER, OF UTICA, NEW YORK.

LAWN-MOWER.

SPECIFICATION forming part of Letters Patent No. 425,687, dated April 15, 1890.

Application filed October 14, 1889. Serial No. 326,947. (No model.)

To all whom it may concern:

Be it known that I, LOUIS MEYER, of Utica, in the county of Oneida and State of New York, have invented a new and useful Improvement in Lawn-Mowers, of which the following is a full, clear, and exact description.

The objects of my invention are to provide novel and efficient means for the accurate and convenient adjustment of the knives on the cutter-head of a lawn-mower and for adjusting the grass-roller, furnish the grass-roller with a cover which is adjustable and adapted to protect said roller from being impeded in its action, provide a throat-slot that is formed in said cover in advance of the roller to discharge grass accumulations through it, and, further, to provide a protecting-guard on the front of the frame of the machine, whereby injurious contact with trees or shrubbery is avoided.

With these ends in view my invention consists in peculiar features of construction and combinations of parts, which will be herein-after described, and indicated in the claims.

Reference is to be had to the accompanying drawings, forming a part of this specification, in which similar letters of reference indicate corresponding parts in all the figures.

Figure 1 is a side elevation of the lawn-mower, having the cover of the multiplying-gear case broken away to expose said gearing. Fig. 2 is a top plan view of the lawn-mower. Fig. 3 is a side elevation of the device in section, taken on the line 3-3 in Fig. 2, viewed in the direction of the indicating-arrows; and Fig. 4 is an enlarged sectional view of one of the knife-supporting heads, the knives in place, and a head-shaft.

A A represent the side pieces of the mower-frame. These are shaped preferably as shown, and one side piece is recessed on its outer face to receive a series of multiplying wheels and pinions therein, this casing or shallow-chamber being covered by a cap-plate A². The side pieces A are held spaced apart by two transverse bolts.

The transverse shaft B serves as an axle for the ground-wheels B', which are mounted thereon loosely, said wheels being ribbed across their peripheral faces. Each wheel B' is hollowed out on the inner face to produce retaining-boxes B² for the ratchet-wheels B³,

which are secured on the axle within these boxes, said wheels having their teeth so cut that the pawls B⁴ will, when depressed by springs B⁵, engage the teeth when the machine is moved forwardly and slide over the teeth without revolving the axle when the machine is moved rearwardly. The largest gear-wheel of the series is fastened upon the end of the axle that projects through the side piece of the frame in which this gear-wheel is located, and, having meshed engagement with the adjacent pinion of the series, is thus adapted to transmit motion from the axle B, through the meshing gear-wheels and pinions A', to the knife-head-supporting shaft a⁴, on which the last wheel of the series of accelerating or multiplying gear is secured.

The ratchet-gearing on the ground-wheels B' is protected by cap-plates c, and against these plates the collars B⁶ are made to impinge loosely, said collars being mounted on the axle and secured thereto adjustably by set-screws, as shown in Fig. 2.

On the inside faces of the side pieces A integral bracket-boxes B⁷ are formed, in which the axle B rotates freely in a forward direction, it being understood from the construction of parts that the ground-wheels may move in either direction forward or rearward.

In front of the ground-wheel B' a transverse cross-roller D is revolvably secured in boxes formed on brackets A⁵, adjustably held to the side pieces A of the main frame by screws passing through slots g in the brackets and engaging the side pieces. A cutter-bar D' is supported directly in front of the roller D, on a bracket-frame of which it is an integral portion. Connected with the cutter-bar a roller-cover D² is formed of a shape to lie curved above the roller and protect it from being obstructed by long grass as it is cut. At each end of the cover D², integral arms D³ of the bracket-frame project upwardly and rearwardly adjacent to the inner faces of the side pieces A, to which these arms are pivoted at d. (See Fig. 3.) The ends of the arms D³ project between the ears D⁴, and are engaged on their top and lower surfaces by the set-screw bolts e, which are inserted in the ears D⁴, formed on the side pieces A, and by their adjustment regulate the height of the cutter-bar D' and cover D². The roller

D being journaled to the main frame on which the cutter-bar-supporting bracket-frame is pivoted to vibrate, it is evident that an adjustment of the bar D' for height will 5 change its distance from the ground on which the roller bears, so that the roller is adapted to maintain the cutter-bar at any desired point from the ground.

At the base of the cover D² a longitudinal slot b is formed therein, which will allow grass as it is cut to pass through it, the direction of revoluble movement of the roller drawing the grass through and carrying it below the tread of the same. The cover, as 15 previously indicated, is designed to prevent grass from entwining about the roller and fouling it so as to obstruct its rotary motion and free progressive movement.

On the transverse shaft a⁴, which is journaled in the side pieces A at each of its ends, 20 three spaced head-blocks C are secured to revolve with it inside of the frame of the machine. These heads are each of a trefoil form in cross-section, the three equally-spaced and 25 similarly-shaped limbs thus produced being adapted to receive the union screw-plugs C' by drilling and tapping holes of proper size in their sides, as shown at f in Fig. 4.

On the opposite threaded ends of the plugs 30 C' the knife-carrying blocks C² are adjustably located, the connection being effected by insertion of the threaded ends of the plugs into tapped holes formed in the blocks, as shown. The union screw-plugs C' have each 35 a middle portion of their bodies enlarged in diameter, producing short cylindrical hubs, which are radially perforated, as shown in Figs. 3 and 4, for the reception of a pin wrench or "spanner," whereby the screws 40 may be critically adjusted and the distance of the knives C³ from the cutter-bar D' regulated closely. The center hubs of the union screw-plugs C' may also be squared, if preferred, as shown in Fig. 2. An ordinary 45 wrench will then be available for their adjustment.

The cutter-knives C³ are of the usual twisted form, which gives to their beveled cutting-edges a shearing action when the cutter-head 50 blocks and attached knives are rotated by the gearing A', whose prime movers are the ground-wheels B'.

On the cross-bar a', that retains the side frame-pieces A spaced apart at the forward 55 ends A³, a pliable cover A⁴, preferably made of vulcanized gum, is placed, which is designed to yield when this advance guard of the machine is thrust against a tree, shrub, or rigid obstruction, thus avoiding injury to 60 growing bushes or trees, as well as protecting the machine from damage to its cutter-knives.

The handle-bar E is provided with slightly-elastic arms E', which are bent as shown in 65 Fig. 2, and have each a series of holes formed near their ends at spaced distances apart to permit a change of position and alteration of

height of the other end of the handle-bar. (Not shown.) By springing the ends of the arms E' inwardly and causing them to engage 70 with opposite holes two projecting pins a³, that are fixed in the side pieces A of the main frame, the edges of the arms resting between the flanges of the plates a² and on shoulders produced on said plates, a proper degree of 75 inclination of the handle-bar from the ground is obtained in a simple manner. Means for a quick detachment of the handle is afforded by the connection described.

From the peculiar construction of the head-blocks C, whereby the knives C³ may be critically adjusted at each end without having to loosen any part of the device, said knives may be caused to sweep close to the sharp edge of the cutter-bar D', and thus cut with 85 a free shearing action all grass standing or prostrate that is brought into contact with the cutter-bar edge by the progressive movement of the mower. The distance between the axial center of the cutter-heads and the 90 edges of the knives being preserved the same as they wear away assures efficiency in action at all times, if the knives are sharp.

As there is no cutting action when the machine is moved backward, the cutter-knives 95 being dormant, injury to the cutting-edges of said knives is avoided when the machine is drawn by its handle to any point for use over pavements or in the road where stones may be encountered.

Having thus described my invention, I 100 claim as new and desire to secure by Letters Patent—

1. In a lawn-mower, the combination, with a knife-supporting shaft, of spaced head-blocks secured thereon, each head-block having a three-limbed center piece, three knife-holding blocks, and three union screw-plugs, which are cut with right and left hand screws and by threaded connection with the limbs 110 of the center piece and the knife-block are adapted to adjust the knife-blocks radially, substantially as set forth.

2. In a lawn-mower, the combination, with a frame, an axle, ground-wheels that are loosely mounted on the axle and made to lock fast to it when the machine is moved forward, and multiplying gearing which transmits motion from the axle to the cutter-head-supporting shaft, of a cutter-head-supporting shaft, cutter-heads mounted thereon, which are each provided with a three-limbed center piece, three knife-blocks, and three union screw-plugs that are adapted to adjust the knife-blocks radially, and twisted shear cutting-knives, substantially as set forth.

3. In a lawn-mower, the combination, with a frame having two side pieces held spaced apart by two bolts, one at each end, multiplying gearing located in a recess in one of the 130 side pieces, an axle, two ground-wheels mounted loosely on the axle and provided with ratchet-gearing, which locks the wheels to the axle when these are forwardly moved and re-

- lease the axle on rearward movement of the machine, of a transverse grass-roller adjustably pivoted on the main frame, a pivoted bracket-frame, to which is secured a cutter-bar and a curved cover for the grass-roller, said cover being slotted longitudinally, a cutter-head shaft journaled in the side pieces of the main frame, three cutter-head blocks mounted on this shaft, each head-block having a three-limbed center piece, three knife-blocks that are secured to the limbs of the center pieces by right and left hand threads on union screw-plugs, and three twisted knives, substantially as set forth.
4. In a lawn-mower, the combination, with the cutter-head blocks, of knife-carrying blocks and reversely-threaded screws for holding the knife-blocks, substantially as shown and described.
5. In a lawn-mower, the combination, with a main frame, of a handle-bar having slightly-

elastic bent arms, which are perforated at spaced intervals near each free end, pins secured in the frame, which are adapted to engage opposite holes in the arms by springing these arms toward each other, and two resting-plates on which the edges of the arms impinge, substantially as set forth.

6. In a lawn-mower, the combination, with the frame and an adjustable roller carried thereby, of an adjustable cutter-bar and guard pivoted on the frame, said guard being provided with a slot, substantially as shown and described.

7. In a lawn-mower, an elastic covering A⁴ 35 for the front cross-bolt of the frame of the mower, substantially as set forth.
